UNITED STATES PATENT OFFICE.

CHARLES OWENS, OF CHATTANOOGA, TENNESSEE, ASSIGNOR, BY DIRECT AND MESNE ASSIGNMENTS, TO MONTAGUE MAILING MACHINERY CO.

ADDRESSING OR MAILING MACHINE.

No. 922,324.

Specification of Letters Patent.

Patented May 18, 1909.

Application filed April 3, 1908. Serial No. 424,948.

To all whom it may concern:

Be it known that I, CHARLES OWENS, citizen of the United States, residing at Chattanooga, Tennessee, have invented certain new and useful Improvements in Addressing or Mailing Machines, of which the following is a specification.

My invention relates to addressing or mailing machines and my object is to provide a machine capable of rapid operation and one which is of simple construction.

The invention consists in the features and combination and arrangement of parts hereinafter described and particularly pointed out in the claims.

In the drawings, Figure 1 is a plan view of the machine. Fig. 2 is an elevation. Fig. 3 is a cross sectional view substantially on the line 3—3 of Fig. 1, and Fig. 4 is a cross sectional view substantially on the line 4—4 of Fig. 1. Fig. 5 is a detail section of one of the printing plates. Fig. 6 is a view of the inking roller.

In carrying out my invention I employ printing plates which I prefer to make of embossed form having the letters or characters raised from the surface of the metal composing the plates, such for instance as is disclosed in my application for Letters Patent of the United States, filed June 20, 1907, # 379959, though it will be understood that while I prefer to use this form of plate I do not limit myself in this respect. These printing plates or like members are arranged in a hopper 1 arranged over a table 2, which is suitably supported and carries hangers 3, in which are journaled the shafts or drums 4 about which a belt 5 passes. This belt extends along the upper surface of the table 2 and beneath the hopper 1, and it is provided with grippers or studs 6 extending therefrom to engage the lowermost printing plate of the pile in the hopper 1, to move it forward for the addressing or printing operation in connection with the article such as an envelop or magazine which is fed into proper position to receive the impression from the printing plate.

It will be observed that the printing plates have depressed side edges and these plates rest upon a support or shelf 6' at the bottom of the hopper 1 said support being held at one end by the wall of the hopper as shown at 7, and extending over the surface of the belt, leaving a slight clearance between its

under side and the upper surface of said belt. The printing plates are wider than the support 6' and their side edges extend down below the support 6' and near the upper side of the belt, leaving a slight clearance. The grippers or studs 6 are so located as to engage the depressed side edges of the printing plate and move them forward one by one from the bottom of the pile. The front wall of the hopper is provided with an opening at 8 for the forward passage of the printing plates. After leaving the hopper and being moved from the support or shelf 6' the printing plate drops upon the endless band and its depressed side edges fall into recesses 9 in said band arranged directly adjacent the grippers or feeding studs 6, and this allows the main or embossed portion of the printing plate to rest firmly upon the upper surface of the endless band to find a substantial backing thereon.

After leaving the hopper the printing plate is inked by the rubber covered periphery 10 of an inking roll 11, journaled in brackets 12 adjustably secured at 13 to the hopper. This inking roller is provided with side flanges 14 of larger diameter than the diameter of the inking surface or periphery 10, and these flanges are so located that they will run upon the upper surfaces of the depressed edges of the printing plates and upon the upper surface of the endless belt, while at the same time the inking periphery 10 of the rollers will contact with the raised or embossed characters to apply the ink thereto. From this construction it will be seen that the plates will be held firmly in position and the ink will be applied accurately and uniformly to the embossed characters, the relation of the inking periphery and the embossed characters being accurately determined and maintained by the flanges of the inking roller arranged as described. The inking periphery of the roller is separated from the flanges by a space 14', on each side in order that the ink may be kept from spreading to the side flanges and thence to the edges or body of the printing plates.

Ink is supplied to the ink roller by a roller 15 in the tank 16, which roller bears upon the periphery 10 of the inking roller above described. It will be observed that the belt is arranged in a horizontal plane with the inked surface of the printing plate

directed upwardly, and this arrangement enables me to place or feed the articles to be mailed or addressed directly upon the printing plates as they come along to be carried thence between the impression rollers which apply the necessary pressure to make the impression. As a representative form of feed mechanism for the articles to be addressed, I show means for feeding envelopes on to the moving band. The hopper or support for the envelopes comprises supports 16', 17, upon which the envelopes rest on edge or in a vertical plane, the right hand edges of the envelopes finding a bearing upon the rail or bar 18 while the left hand edges of the envelopes lie adjacent the feed roller 19 arranged upon an upright shaft 20 journaled in a bracket 21 extending from the frame or table 2. This shaft carries near its lower end a disk 22, which is borne upon by the belt 5, so that it together with the feeding disk or roller 19 is driven by the movement of the belt. The envelopes are thrust against this feed roller by a feeding device consisting of a roller 22' carried by a swinging arm 23 pivotally mounted in a bracket 24 secured to the table 2 of the machine. This roller has a ratchet wheel 25 at its upper end engaged by a spring pawl 26. The swinging bracket is returned to the position shown in Fig. 1, after being operated, by a spring 27.

For operating the feed roller I provide pins 28 extending up from the belt, the said pins being in line with a depending pin 29 of the swinging bracket 23, so that when a printing plate which has been inked arrives in position opposite the hopper or feeding in place for the envelopes or other articles the pin 28 of the belt will strike the depending pin 29 of the swinging bracket and turn the same, thus moving the roller 22' toward the left from the position shown in Fig. 1, and as this roller is composed of gelatin, or has a gelatin surface it will by engaging the foremost envelop move the same toward the left so that its end edge will strike the periphery of the feed roller 19 and this end will be moved inwardly by this roller. The roller 22' on this movement will be held against rotation by the pawl engaging the ratchet wheel, but after the pin 28 disengages itself from the pin 29 the spring 27 will return the swinging frame 23 back to normal position shown at Fig. 1 and in this movement the roller 22' can turn freely and thus simply roll with its surface upon the envelop. The envelop which has been thrust toward the left however, will be by the action of the roller 19, turned over upon the belt and will feed on to the printing plate and will immediately pass therewith between the impression rollers 30, 31, these rollers being journaled in suitable bearings connected with the

table 2. The impression is made by these rollers and after passing them the envelop passes up an incline 33 while the printing plate or stencil passes into a hopper 34 through an opening in the incline indicated in dotted lines immediately to the left of the roller 30 in Fig. 1.

I provide at 35 a roller or disk arranged with its side face in a vertical plane and bearing upon the edge of the traveling belt. The outer face of this roller serves as the stop against which the envelopes bear, the said envelopes also finding a bearing near their upper portions against the end of the bracket 24. This disk 35 also serves to feed the envelop toward the left in Fig. 1, and it affords a bearing also for the edge of the belt to prevent the said belt from being deflected laterally at this point by reason of the pin 28 contacting with the pin 29. The pin 28 is secured in a metal plate 36, embedded in the traveling band and this plate bears at its end on the side face of the wheel or disk 35. I also provide a roller at 36' for supporting the belt at a point directly below the inking roller. The roller 35 derives its motion from contacting with the belt, and of course this is true also of the feed roll 19 and the rotation of the inking roll and the impression rolls also depends upon the traveling movement of the belt.

It will be understood that instead of having the carrier belt arranged to pick up the printing plates, I may employ an endless belt having printing plates or type surfaces carried permanently thereby, said belt thus forming in effect a traveling or rotary press member coacting with the pressure roll to make the impression.

I claim as my invention:—

1. In combination, an endless belt or carrier for the printing members, a hopper, inking means, said belt having a horizontal portion, means for feeding the articles to be addressed or mailed upon the said horizontal portion when the printing member arrives at this point, and impression means, said articles being fed upon the printing members in advance of the impression means and independently thereof substantially as described.

2. In combination a hopper for the printing plates, which plates consist of sheet material having its side portions extending downwardly and thence outwardly forming marginal continuations out beyond and depressed in relation to the main part of the plates, and a carrier having a plain surface with recesses therein to receive said depressed edges, and means projecting from the surface of the carrier for engaging and moving the plates from the hopper, substantially as described.

3. In combination, a hopper having a support for the main portion of the printing

105

130

plate leaving its side edges depending, and a carrier having means to engage the depending side edges of the printing plate, substantially as described.

5. In combination, a hopper having a support to engage the main part of the printing plate, leaving its side edges depending and a carrier having means to engage the depending side edges and having a supporting surface for the main portion of the plate, substantially as described.

10. In combination, a hopper having a support for the main portion of the printing plate, leaving its side edges depending and a recessed carrier to receive the said side edges and furnish a support for the main part of the printing plate with means for engaging the depending edges of the printing plate to move it from the hopper, substantially as described.

15. In combination in apparatus of the class described, a carrier having recesses to receive the depressed edges of the printing plates, means thereon for engaging the printing plates and an inking roll having flanges to engage the depressed edge portions of the printing plates while lying in said recesses, and an intermediate peripheral portion to apply ink to the printing plate, substantially as described.

20. In combination in apparatus of the class described, an endless carrier or belt, a hopper for the printing plates, said printing plates having depressed edge portions and the said carrier or belt having recesses to receive the same, and an inking roller having flanges to engage the edge portion of the printing plates, and an intermediate inking periphery to engage the main part of the printing plate which finds a backing against the carrier or belt, substantially as described.

25. In combination with a carrier having a recess or recesses to receive depressed portions of a printing plate and an inking roller to engage the main part of the plate which finds a backing against the carrier, said carrier moving the printing plate to and past the inking roller substantially as described.

30. In combination with printing plates having depressed lateral edges, a hopper for holding said printing plates, an endless carrier moving under the hopper and having recesses to receive the depressed edges of the printing plates to carry them in the direction of the lines of characters thereon, means for holding the articles to be addressed on edge alongside of the endless carrier, and means for feeding the articles in a direction transversely of the movement of the said carrier and onto the upper faces of the printing plates, substantially as described.

35. In combination with the carrier for the printing plates and which also serves as a carrier for the article to be addressed, feed-

ing mechanism for the articles to be addressed and means on said carrier for operating said feed mechanism, substantially as described.

40. In combination with the carrier for the printing plates, means for holding the articles to be addressed, a feed roller, an oscillating support therefor, means for holding the roller against rotation in one direction but allowing said roller to rotate when the support swings back to normal position, and means for operating the said support from the carrier, substantially as described.

45. In combination in apparatus of the class described a carrier for the printing plates, a feed roll for the articles to be addressed, means for holding the said roll against rotation in one direction, a carrier for said roll having a back and forth movement, the said roll being free to turn as it moves backwardly, and means for operating the carrier of the roller from the printing plate carrier substantially as described.

50. In combination with the carrier for the printing plates, means for holding the articles to be addressed adjacent thereto, a feed member having a back and forth movement in the direction of the feed to engage the articles and a pin on the carrier to engage the said feed member, and move it forward in the direction of the feed substantially as described.

55. In combination with the carrier for the printing plates, a feed member for the articles to be addressed comprising a pivoted support having a portion to contact with the said articles said support having swinging movement in the direction of the feed and a pin on the carrier to operate the said pivoted support and free itself therefrom, substantially as described.

60. In combination with the endless carrier for the printing plates having a portion extending in one plane, means for supporting the articles on edge adjacent and laterally of the said portion of the endless carrier, and means for tipping the articles in a direction transverse to the carrier and over upon the printing plate on the carrier, substantially as described.

65. In apparatus of the class described, an endless carrier for the printing means having a horizontally extending portion, means for holding the articles to be addressed on edge along side the said carrier and a roller to engage the forward end of the articles to tip the same over upon the carrier, substantially as described.

70. In apparatus of the class described, an endless carrier having a horizontally extending portion and having thereon the printing devices, means for holding the articles to be addressed on edge along side the said carrier and a roller to engage the forward end of the articles to tip the same over upon the carrier, substantially as described.

- said roller being operated from the movement of the carrier, substantially as described.
18. In combination, the endless carrier having a horizontal portion and having thereon the printing devices, means for supporting the articles to be addressed adjacent said carrier, a device for tipping the articles over upon the said carrier, and a device having a back and forth movement for moving the articles against the tipping device, said back and forth movement resulting from the movement of the carrier substantially as described.
19. In combination, the endless carrier having a horizontal portion and having thereon the printing devices, means for supporting the articles to be addressed adjacent said carrier, a device for tipping the articles over the said carrier, and a device having a back and forth movement for moving the articles against the tipping device, said back and forth device being operated from the carrier, substantially as described.
20. In combination in apparatus of the class described, the endless carrier for printing plates, an impression roll, a stationary incline extending over the endless carrier to receive the articles therefrom and up which the articles pass after leaving the impression roll, and a receptacle to receive the printing plates from the endless carrier, substantially as described.
21. In combination in apparatus of the
- class described, the endless carrier for printing plates, an impression roll, an incline up which the articles pass after leaving the impression roll, and a receptacle to receive the printing plates from the endless carrier, said incline having an opening for the passage of the printing plates, substantially as described. 35
22. In combination in apparatus of the class described, an endless carrier belt, means for holding the articles on edge along side the same, said belt having means for holding the printing plates and a disk rotating in a vertical plane by engagement with the edge of the endless carrier and furnishing a bearing on its outer face for the articles to be addressed, substantially as described. 45
23. In combination with the endless carrier belt for the printing plates, means for holding the articles to be addressed on edge along side said belt, a pivotally mounted member for feeding the articles, a pin on the belt for operating the said member and a disk affording a side bearing for the belt and rotated thereby, said disk furnishing a bearing for the articles to be addressed and tending to feed them forward, substantially as described. 55 60

In testimony whereof I affix my signature in presence of two witnesses.

CHARLES OWENS.
